(57) **CLAIM**

The ornamental design for a jigging spoon, as shown and described.

DESCRIPTION

FIG. 1 is left side perspective view of a jigging spoon in accordance with the present invention;

FIG. 2 is a right side perspective view of the jigging spoon of FIG. 1;

FIG. 3 is a front elevation of the jigging spoon of FIG. 1; FIG. 4 is a rear elevation of the jigging spoon of FIG. 1; FIG. 5 is a right side elevation of the jigging spoon of FIG. 1; the left and right side being mirror images of each other; FIG. 6 is a top plan view of the jigging spoon of FIG. 1, FIG. 7 is a bottom plan view of the jigging spoon of FIG. 1; FIG. 8 is a left side perspective view of an alternative embodiment of the jigging spoon;

FIG. 9 is a right side perspective view of the jigging spoon of FIG. 8;

FIG. 10 is a front elevation of the jigging spoon of FIG. 8; FIG. 11 is a rear elevation of the jigging spoon of FIG. 8; FIG. 12 is a right side elevation of the jigging spoon of FIG. 8; the left and right side being mirror images of each other; FIG. 13 is a top plan view of the jigging spoon of FIG. 8; and,

FIG. 14 is a bottom plan view of the jigging spoon of FIG. 8.

The features shown in broken lines in FIGS. 8-9 depict environmental structure only and form no part of the claimed design.
